UNITED STATES PATENT OFFICE.

GEORGE A. BURNHAM, OF SAUGUS, MASSACHUSETTS, ASSIGNOR TO SEARS B. CONDIT,
JR., OF BROOKLINE, MASSACHUSETTS.

RENEWABLE FUSE.

1,404,576.

Specification of Letters Patent. Patented Jan. 24, 1922.

Application filed October 4, 1918. Serial No. 256,797.

To all whom it may concern:

Be it known that I, GEORGE A. BURNHAM, a citizen of the United States, residing at Saugus, in the county of Essex and State of 5 Massachusetts, have invented an Improvement in Renewable Fuses, of which the following is a specification.

My invention relates to electric fuses and has more particular reference to fuses of the 10 refillable type in which the fusible element thereof is replaceable upon necessity by a new fusible element.

In refillable fuses it is universal practice to inclose the fusible elements thereof in a 15 tube or cylinder of non-conducting material such as fibre and to provide various means for sealing or completely enclosing the fuse therein which, however, will permit the opening of said tube for the renewal of a 20 burned fusible element.

Many types of refillable or renewable fuses are on the market all of which are more or less complicated and very expensive to manufacture. All of these refillable fuses 25 are designed to fit the standard type of fuse clip adapted to receive an inclosed tubular fuse.

The object of my invention is in the provision of a renewable fuse which has all the 30 advantages of the inclosed refillable fuse and which is adapted to be received in the standard tubular fuse clips.

Briefly, I accomplish the object of my invention by providing a tube having open 35 ends through which the fusible element is adapted to be extended and thereby protected by the walls of the tube, the tube thereby forming a tubular barrier entirely surrounding the fusible element. Ferrules 40 or end caps are arranged on the tube, at the extremities thereof and may have ears or the equivalent thereon, between which the fusible link or element is adapted to be detachably connected, whereby upon the fusing 45 of a link, a second link may be secured thereto to again condition the fuse for operation.

By reason of the tubular barrier surrounding the fusible element, all of the advantages 50 of the enclosed type of fuse are retained and, by reason of the open ends of the tube the desirable "expulsion" action occurs upon the blowing of the fuse, thereby aiding in the extinguishment of the arc.

Furthermore, by this construction, a very 55 simple and inexpensive type of renewable fuse is obtained and in which the renewable fusible element is easily replaced.

Certain features of this invention are shown but not claimed in my co-pending application Serial No. 247,976, filed August 2, 1918.

Fig. 1 is a side elevation of a renewable fuse embodying my invention as associated with a fuse block shown partly in section. 60

Fig. 2 is a sectional elevation of the fuse of Fig. 1.

Fig. 3 is perspective view of an end of the fuse.

As here shown, the renewable fuse includes 70 the tubular casing 10 of an insulating material such as fibre having a relatively large internal diameter which may vary according to the capacity of the fuse and a length which also may vary according to the capacity of 75 the fuse. Said tube is open at each end. Cylindrical end caps or ferrules 11 are arranged on said tube at the extremities thereof and are of a diameter and width corresponding to the end caps or ferrules of the standard type of inclosed fuse whereby the fuse may be received in the standard tubular fuse clips shown at 12 as arranged on a standard type of fuse block 13.

Each of said end caps or ferrules 11 may 85 be provided with a reflexed portion or ear 14 which is upturned and extended towards each other above the body of the fuse. Each ear 14 is provided with attaching means, as screws 15, by means of which the extremities 90 of a fuse link 16 may be secured thereto.

Said fuse link 16 may comprise a strip of fuse wire or other fusible element of relatively small cross-section extended through said tube 10 and the ends thereof brought 95 up and secured to the ears 14 of the end caps or ferrules 11, the main body of the fuse 16 being approximately in the center line of the tube 11 and because of the relatively great internal diameter of the casing, as contrasted with the relatively small cross-section of the fusible element, said element is a relatively great distance from the side-wall of the casing.

A refillable fuse constructed as above described performs all the functions of the renewable inclosed fuse at present constructed. The tube 10 forms a tubular barrier sur-

rounding the fusible element thereby inclosing the fuse and preventing the arc resulting from the fusing of one element from effecting an adjacent fusible element. Furthermore this type of fuse has advantages peculiar to itself. By the provision of the open ends of the tube 10, an explosive operation of the fuse is obtained whereby, when the fuse blows or fuses, the hot gases are forcibly driven from the ends of the tubes thereby quickly to quench the arc.

By the provision of the reflexed ears forming connecting means between the end ferrules for the fuse, the connecting means do not extend beyond the extremities of the tubular portion, and the fuse may thereby be used in any fuse block adapted to receive a standard tubular inclosed fuse, such, for instance, as shown in Fig. 1, having the barrier 20 of insulating material arranged in closed proximity to one of the fuse clips. If connection between the fusible element 16 and the end caps or ferrules 11 were otherwise made, this connection might protrude from the end of the fuse and interfere with

the proper arrangement of the fuse within the fuse clip 5.

I claim:

A refillable fuse comprising a tubular insulating casing having a relatively large internal diameter and open ends, end ferrules carried on the outside of said casing at the ends thereof having oppositely disposed upwardly extended ears with fuse-element attaching means thereon, and a fusible element having a relatively small cross-section as compared with the internal diameter of said casing disposed within said casing and spaced from the side-wall thereof having its ends extended through the open ends of the casing and upwardly and secured to the ears of said end ferrules.

In testimony whereof, I have signed my name to this specification, in the presence of two subscribing witnesses.

GEORGE A. BURNHAM.
